Primary Examiner—Doris V. Coles*Assistant Examiner*—Linda Brooks*Attorney, Agent, or Firm*—Frishauf, Holtz, Goodman, Langer & Chick[57] **CLAIM**

The ornamental design for a rack, as shown and described.

DESCRIPTION

FIG. 1 is a front, top, left side perspective view of a rack, showing my new design;

FIG. 2 is a top plan view thereof;

FIG. 3 is a front elevational view thereof;

FIG. 4 is a left side view thereof, the right side view being a mirror image;

FIG. 5 is a rear elevational view thereof;

FIG. 6 is a bottom plan view thereof;

FIG. 7 is a front, top, left side perspective view of a second embodiment thereof;

FIG. 8 is a top plan view thereof;

FIG. 9 is a front elevational view thereof;

FIG. 10 is a left side view thereof, the right side view being a mirror image;

FIG. 11 is a rear elevational view thereof; and,

FIG. 12 is a bottom plan view thereof.

In the drawings, the portions shown in dashed lines do not form part of the claimed design. The showing of CD cases in dashed lines in FIGS. 1 and 7 is for illustration purposes only. The CD cases do not form part of the claimed design.
